UNITED STATES PATENT OFFICE.

CLARENCE E. ATKINS, OF EAST PROVIDENCE, RHODE ISLAND, ASSIGNOR, BY MESNE ASSIGNMENTS, TO THE WATERBURY FARREL FOUNDRY AND MACHINE CO., OF WATERBURY, CONNECTICUT, A CORPORATION OF CONNECTICUT.

WIRE-DRAWING MACHINE.

Application filed November 18, 1924. Serial No. 750,648.

To all whom it may concern:

Be it known that I, CLARENCE E. ATKINS, a citizen of the United States, residing at East Providence, in the county of Providence and State of Rhode Island, have invented certain new and useful Improvements in Wire-Drawing Machines, of which the following is a specification.

This invention relates to improvements in the construction and operation of wire-drawing machines, and has for its object to provide simple and effective means whereby the drawing-in action of the mechanism may be started very slowly so as not to rupture the wire and then accelerated to speed up the action of the machine.

—A further object of the invention is a provision of means for returning the wire-engaging members to their starting point and reducing the speed of this return stroke ready for the next initial draft stroke.

The invention further consists in the provision of a pair of speed control clutches which are driven at different speeds, the higher speed clutch being moved to take up the draft load gradually and speed it up away from the driving action of the slower clutch so as not to rupture the work during the change of speed.

A still further object of the invention is a provision of latch and tripper mechanism through which the clutch mechanism is operated by the traveling movement of the wire grippers, both on its draft stroke and return stroke.

With these and other objects in view, the invention consists of certain novel features of construction, as will be more fully described and particularly pointed out in the appended claims.

In the accompanying drawings:—

Figure 1 is a plan view of a wire-drawing machine with my improved accelerating and retarding mechanism applied thereto.

Figure 2 is a side elevation of the mechanism illustrated in Figure 1.

Figure 3 is a perspective view of the latch and tripper mechanism.

Figure 4 is a sectional side elevation show-

ing one of the latches and a spring normally pressing the latch into engaged position.

Figure 5 is a face view of the roll controlled clutch.

Figure 6 is a diagrammatic view illustrating the driving clutch mechanism through which the accelerating and retarding speeds of the wire gripping members are obtained.

A wire drawing machine of this character particularly that operating on hollow wire is usually obliged to start its draft stroke slowly so as not to rupture the wire in starting the same through the draw plate and this slow draft stroke continues throughout the length of the stroke, which movement is found to be considerably slower than the wire will stand after it has been started, and therefore the production of the machine is considerably curtailed, to obviate which difficulty, I have arranged mechanism whereby the initial draft stroke will be very slow and directly after having been started, I have provided means for greatly accelerating this stroke, also I have provided means whereby the last end of the return stroke of the wire-drawing mechanism is caused to reset the mechanism so that the next initial draft stroke will be slow; and the following is a detailed description of the present embodiment of my invention showing one means by which these advantageous results may be accomplished:—

With reference to the drawings, 10 designates the frame of the usual wire-drawing machine on which is slidably mounted a pair of wire gripping jaws 11 which are operated to slide along the face of the frame by means of a chain 12 which is fast to the rear thereof and passes over the sprocket 13 at the rear end of the machine thence around the sprocket at the front end of the machine back to engage the portion 71 of the jaw-carrying mechanism, whereby these jaws may be moved to make a draft stroke and then return to their starting position to engage the end of the next piece of wire to be drawn.

As it is found in practice of advantage,

to start the draft stroke slowly and subsequently accelerate the same to increase the production of the machine, I have provided a driving mechanism which is diagrammatically laid out in Figure 6, the same comprising a main driving pulley 15 mounted on the drive shaft 16 to be driven by a belt from any convenient source. On this shaft is fixed a relatively small gear 17 engaging a larger gear 18 for imparting a relatively slow movement to the jack shaft 19 through the roll clutch 20, a part of which is shown as being carried by large gear 18. This roll clutch is provided with an inner disk 21 which is keyed to the shaft 19 and on the face of the gear 18 are mounted a plurality of spring-pressed rollers 22 for engaging the face of the disk 21 through which shaft 19 may be driven. On shaft 16 is also fixed a larger gear 23 which meshes with a smaller gear 24 loosely mounted on the jack shaft 19. On the face of this gear 24 is a cone clutch member 25 adapted to be engaged by a sliding clutch member 26 keyed to shaft 19, whereby when it is desired to speed up shaft 19 over that imparted to it through gears 19 and 18 and clutch 20, I throw clutch member 26 into engagement with its opposite clutch member 25 and through gears 23 and 24 this shaft 19 is accelerated. The chain 12 is driven through the sprocket gear 13 and a draft motion is imparted to this sprocket wheel and chain through worm gear 27, worm 28, worm shaft 29, clutch gear 30, and gear 31 mounted on the jack shaft 19 and a reverse or return motion of this sprocket and chain, and wire gripping member is imparted through gears 32 fixed to jack shaft 19, idler gear 33 and clutch gear 34.

A clutch member 35 is positioned between clutch gears 30 and 34, whereby a movement in one direction engages clutch member 36 to drive the grippers on their draft stroke and in the opposite direction to engage clutch member 37 to return the grippers to their starting point and this clutch member 35 may be operated through the fork 38, rod 39, cross rod 40 and slide rod 41 on which latter rod is mounted the operating handles 42 and 43 so that a man standing at either end of the machine may by operating handle 42 or 43 either stop or start the travel of the driving mechanism in either direction.

In order to control the retarding action of the jaws at the latter end of the return stroke and the accelerating of the draft stroke directly or soon after starting through the operation of the roll clutch 20 and the friction clutch 26, I have provided a latch and tripper mechanism 44 which is mounted on the slide bar 53 in guides 54 and 55 on the side of the frame 10, this tripper mechanism comprising a pair of spring pressed latches

45 and 46 mounted to slide endwise in the housing 47, each being pressed by a spring 48 to their normal raised or engaging positions, latch 46 being provided with a block 49 on its lower end having an inclined face 70 so that when moved into engagement with the fixed block 50, it will be drawn downwardly into position illustrated in Figure 3, and when the mechanism is moved in the opposite direction this latch 46 will be released 75 and block 52, on the lower end of latch 45, will engage fixed block 51 and be withdrawn from its engaging position. This slide bar 53 is provided with a rack 56 which is engaged by a segmental gear 57 pivoted at 58 on the frame which segment is provided with an offset crank pin 59 which is engaged by a connecting rod 60 which rod is connected to operate the clutch member 26 on the jack shaft 19, through the rod 61, connector 62, knee lever 63, rod 64 and connector 65. On the carriage 72 to which the jaws 11 are connected, is mounted a tripper plate 66, the rear edge 67 of which engages the upwardly extending latch 45 soon after the gripping jaws start on their draft stroke and thus cause this tripper mechanism with its bar 53 and its rack 56 to rotate the segmental gear 57 and so move the clutch member 26 into engagement with the clutch gear 24, whereby the accelerating motion of this clutch gear 24 is driven through gear 23 causing the jack shaft 19 to be accelerated in its speed and through gears 31 and 30 to at once accelerate the draft speed of the gripping jaws, the main drive clutch 35 being of course connected. After this the tripper plate 66 in moving the bar 53 to the left causes the block 51 to engage block 52. After the clutch 26 has been 100 thrown in and the speed accelerated, the block 51 engages block 52 and withdraws the latch permitting the plate 66 to pass thereover and along the frame to the end of its draft stroke. Then upon the return of the jaws, the end 70 of this plate 66 engages the now raised latch 46 and causes the bar 53 to move in position to advance, and through rack 56, segment 57 and its connections above described, throws the clutch 26 from engagement with the clutch gear 24 permitting the roll gear 18 to again assume a slow driving motion of the mechanism ready to again produce a relatively slow initial draft stroke to the operating jaws. And this operation 110 of slow starting and subsequently accelerating the speed of the draft stroke is automatically repeated at each operation of the machine.

The draw bench herein described and illustrated is of the reversing type, but my invention of accelerating the speed of the draw stroke may be applied equally well to any of the well known types of draw benches.

My improved attachment for a wire drawing machine is very simple and practical and is effective in its operation and by its use the production of the machine is greatly increased.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a draw bench, longitudinally-traveling wire grippers operatively mounted on said bench, mechanically-actuated means for initially imparting a slow drawing-in movement to the grippers, means for subsequently accelerating this movement, and means for returning said grippers after each drawing-in stroke.

2. In a wire bench, longitudinally-traveling wire grippers operatively mounted on said bench, a two-speed driving mechanism operated to initially impart a relatively slow drawing-in movement to said grippers and subsequently accelerating the same, and means for returning said grippers after each drawing-in stroke.

3. In a draw bench, longitudinally-traveling wire grippers operatively mounted on said bench, means for initially imparting a relatively slow drawing-in movement to said grippers, and friction clutch driven mechanism for subsequently accelerating the same.

4. In a draw bench, longitudinally-traveling grippers operatively mounted on said bench, means for starting said grippers on their drawing-in stroke at a slow speed, automatically actuated means for shifting the driving mechanism to increase its draw speed directly after starting, and means for returning said grippers after each drawing stroke.

5. In a draw bench, longitudinally-traveling wire engaging members operatively mounted on said bench, means for imparting a drawing-in and a return movement of said members, friction means operated by said drawing-in movement for flexibly accelerating said movement directly after having started, and means for resetting the slow starting mechanism just prior to finishing the return movement.

6. In a draw bench, longitudinally-traveling wire engaging members operatively mounted on said bench, means for imparting a drawing-in and a return movement of said members, clutch controlled mechanism for accelerating said drawing-in movement directly after having started, and latch and tripper mechanism operated by said drawing-in movement for controlling the action of said clutch mechanism to increase the working speed.

7. In a draw bench, longitudinally-traveling wire-engaging members operatively mounted on said bench, means for initially imparting a relatively slow draft motion to said members, means including a friction clutch for subsequently and yieldingly accelerating said movement, and means for resetting said draft operating mechanism at the end of its return stroke to again impart said slow initial motion.

8. In a draw bench, longitudinally-traveling wire engaging members operatively mounted on said bench, a relatively slow driving clutch, a relatively fast driven clutch, means for operating through said first clutch to impart a relatively slow initial draft motion to said members and subsequently operate through said second clutch to yieldingly increase said draft speed, means for returning said members, and means operated by said return stroke adjacent the end thereof for releasing the fast clutch and engaging the slow clutch to impart a slow initial motion to the next succeeding working stroke.

9. In a draw bench, longitudinally-traveling wire-engaging members, a relatively slow driving clutch, a relatively fast friction driven clutch, means for operating through said first clutch to impart a relatively slow initial draft motion to said members, automatically shifting means subsequently operating through said second clutch to yieldingly increase said initial draft speed, means for returning said members, and tripper mechanism operated by said return stroke adjacent the end thereof for releasing the fast driving clutch and engaging the slow clutch to impart a slow initial motion to the next succeeding draft stroke.

10. In a draw bench, longitudinally-traveling wire engaging members operatively mounted on said bench, means for imparting a drawing-in and a return movement of said members, clutch controlled mechanism for accelerating said drawing-in movement directly after having started, and means operated by said drawing-in movement for controlling the action of said clutch mechanism to increase the working speed.

11. In a draw bench, longitudinally-traveling wire engaging members operatively mounted on said bench, means for initially imparting a relatively slow draft motion to said members, means including a friction clutch for subsequently and yieldingly accelerating said movement, and means for resetting said draft operating mechanism after having finished the working stroke.

12. In a draw bench, longitudinally-traveling wire engaging members operatively mounted on said bench, a relatively slow driving clutch, a relatively fast driven clutch, means for operating through said first clutch to impart a relatively slow initial

- draft motion to said members and subsequently operate through said second clutch to yieldingly increase said draft speed, means for returning said members, and 5 means operated after having finished the working stroke for releasing the fast clutch and engaging the slow clutch to impart a slow initial motion to the next working stroke.
- 10 13. In a draw bench, longitudinally-traveling wire engaging members, a relatively slow driving clutch, a relatively fast friction driven clutch, means for operating through said first clutch to impart a relatively slow initial draft motion to said members, automatically shifting means subsequently operating through said second clutch to yieldingly increase said initial draft speed, means for returning said members, 15 and means operated after having finished the working stroke for releasing the fast driving clutch and engaging the slow driving clutch to impart a slow initial motion to the next succeeding draft stroke.
- 20 14. In a draw bench, longitudinally-traveling wire grippers operatively mounted on said bench, mechanically-actuated means for initially imparting a slow drawing-in movement to the grippers, and faster driving means for taking up the load of the 25 slower driving means before rendering the driving action of the slower driving means ineffective.
- 25 15. In a draw bench, longitudinally-traveling wire grippers operatively mounted on said bench, mechanically-actuated means including a detent clutch for initially imparting a slow drawing-in movement to the grippers and faster driving means for taking up the load from said clutch to render 30 its driving action ineffective.
- 35 16. In a draw bench, longitudinally-traveling wire grippers operatively mounted on said bench, and mechanically-actuated means for imparting a plurality of different speeds to said grippers during their working 35 stroke.
- 40 17. In a draw bench, longitudinally-traveling wire grippers operatively mounted on said bench, mechanically-actuated means for initially imparting a relatively slow drawing-in movement to the grippers, and means for subsequently accelerating this movement.
- 45 18. In a draw bench, longitudinally-traveling wire grippers operatively mounted on said bench, mechanically-actuated means for initially imparting a relatively slow drawing-in movement to the grippers, means for subsequently accelerating this movement, 50 means for returning said grippers after each drawing-in stroke, and means for resetting the operating mechanism after the finish of each working stroke and before the start of the next working stroke to impart to the grippers their original starting speed.
- 55 19. In a draw bench, longitudinally-traveling wire engaging members operatively mounted on said bench, means for initially imparting a relatively slow draft motion to said members, means including a friction clutch for accelerating said movement, and means for resetting said draft operating mechanism preparatory to again imparting said slow initial motion. 70
- 60 20. A wire drawing machine having a wire gripper adapted to have reciprocal movement, a tripper plate affixed to the gripper, a rack bar carried by the tripper plate, a pivoted toothed segment in engagement with the rack bar, variable speed gears for controlling the speed of the gripper and clutches for engaging the gears, said clutches being operably related to the segment. 75
